John W. Quynn,

By *Cashow & Co.*

Attorney

UNITED STATES PATENT OFFICE.

JOHN WILLIAMS QUYNN, OF PARKERSBURG, WEST VIRGINIA.

GOLF CLUB.

Application filed September 4, 1928. Serial No. 303,856.

This invention relates to golf clubs and aims to provide means forming a part of a club, to impart over-spin or back-spin to the ball struck by the club.

5 Another object of the invention is to provide a club having a resilient striking face formed preferably of spring steel so that a movement of the striking face will be permitted, independently of the club head.

10 With the foregoing and other objects in view which will appear as the description proceeds, the invention resides in the combination and arrangement of parts and in the details of construction hereinafter described

15 and claimed, it being understood that changes in the precise embodiment of the invention herein disclosed, may be made within the scope of what is claimed, without departing from the spirit of the invention.

20 Referring to the drawing:

Figure 1 is a front elevational view of a golf club having a resilient striking face constructed in accordance with the invention.

Figure 2 is a sectional view taken on line 25 2—2 of Figure 1.

Figure 3 is a perspective view of an iron club having a resilient striking face.

Figure 4 is a sectional view taken on line 4—4 of Figure 3.

30 Figure 5 is a perspective view of a metallic driver head having an integral resilient striking surface.

Referring to the drawing in detail, Figures 1 and 2 illustrate the invention as attached to 35 a wooden club such as a driver, brassie or spoon, the head of the club being indicated by the reference character 5.

The attachment embodies a metal plate 6 formed with openings to receive the securing 40 screws 7 that secure the attachment to the club head 5. Forming a part of the plate is an upstanding flange 8 of a length to extend to a point adjacent to the upper edge of the club head, as clearly shown by Figure 2 of the 45 drawing.

This flange is formed of spring steel material and has a downwardly extended flange 9 forming a part thereof, the flange 9 being inclined outwardly towards the base of the club 50 so that a lofting surface is presented, however it is to be understood that the pitch of the flange 9 may be regulated for the type of club with which the attachment is to be used.

A substantially wide space is provided between the lower end of the flange 9 and the 55 flange 8 thereby permitting of movement of the lower edge of the flange 9, to accomplish the purpose of the invention, when the club is in use, it being evident that when a ball is struck with the club, the flange 9, being 60 formed of spring steel material will move inwardly under the impact of the blow and will immediately assume its natural position imparting thrust to the ball in an upward direction to give the ball over-spin and greatly increasing the length of the shot.

In the form of the invention as shown by Figures 3 and 4 of the drawing, the idea is carried out in the construction of an iron club head, in the present showing the iron is of 70 the lofting type.

The blade is formed with a groove or slotted portion 10 extending throughout the width of the blade and disposed between the front and rear surfaces thereof, defining a 75 forward striking surface 11 or flange that extends an appreciable distance above the upper end of the rear flange 12, and since the blade is constructed of spring steel, it is obvious that the blade will move in the direction 80 of the arrow as shown by Figure 4 under the impact of the blow, when the striking surface returns to its initial position, to impart back-spin to the ball struck so that the ball will stop at its point of contact with the ground surface 85 or green onto which the ball is pitched, reducing forward roll of the ball, to the minimum.

The driver as shown by Figure 5 includes a hollow casing 13 and a forward depending flange 14 formed integral therewith and 90 spaced from the body of the club head so that over-spin will be imparted to a ball on the drive.

I claim:

1. In a golf club, a head, a flange formed of 95 spring metal extending from one of the longitudinal edges thereof and extending in substantially parallel relation with the head in spaced relation therewith, one edge of the flange and the ends of the flange being free 100 from the head.

2. In a golf club, a head, a flange extending upwardly from one of the longitudinal edges of the head and disposed in parallel spaced 105 relation with the head, the free edge of the flange extending an appreciable distance be-

yond the upper edge of the head to provide a resilient striking surface, and the ends of the flange being free from the head.

3. In a golf club, a flange formed of spring metal extending upwardly from the lower longitudinal edge of the head, the upwardly extended flange being disposed in spaced relation

with the head throughout its length and width to provide a striking surface.

In testimony that I claim the foregoing as my own, I have hereto affixed my signature.

JOHN WILLIAMS QUYNN.
